WINDOW

Henry N. Renton, Jenkintown, Pa., assignor to
Hunter Manufacturing Company, Bristol, Pa.,
a corporation of Delaware

Application May 4, 1945, Serial No. 591,882

9 Claims. (Cl. 189—64)

1

This invention relates to windows, and has reference more especially to supplemental windows with slideable auxiliary storm and/or screen sashes adapted for use in connection with the permanent windows of dwellings and other buildings.

My invention has for its chief aim the provision of a supplemental window of the kind referred to which lends itself to manufacture at relatively small cost; which can be easily installed without entailing the use of any special tools other than an ordinary screw driver or the like; which is adjustable so that slight inaccuracies in the nominal dimensions of the frames of standard permanent windows can be compensated for and the need for fitting dispensed with; and from which the sashes can be readily and quickly removed from within doors when interchanges are to be made at different seasons of the year.

How the foregoing and other advantages are realized in practice will appear from the following description of the attached drawings, wherein Fig. 1 is an outside elevation of a permanent window to which my improved supplemental window unit has been applied.

Fig. 2 is a broken-out vertical section of the organization on a much larger scale taken as indicated by the angled arrows II—II in Fig. 1.

Fig. 3 is a vertical detail section taken as indicated by the angled arrows III—III in Fig. 1.

Figs. 4, 5 and 6 are fragmentary detail views in horizontal section taken as indicated respectively by the angled arrows IV—IV, V—V and VI—VI in Fig. 1.

Fig. 7 is a fragmentary detail view looking as indicated by the angled arrows VII—VII in Figs. 3 and 6.

Fig. 8 is a perspective view showing one of the component elements of the supplemental window; and

Fig. 9 is a view corresponding to Fig. 2 showing a complete vertical section through the main and supplemental windows on a reduced scale and the manner in which the auxiliary sashes can be removed or placed from within-doors.

In these drawings the lintel, the sill and the jambs of the frame of the ordinary permanent wooden window are respectively designated by the numerals 10, 11 and 12, and the usual upper and lower sliding sashes by the numerals 13 and 14. After common practice the sill 11 is downwardly sloped for water shedding as at 15 and provided with the customary stop shoulder at 16.

The supplemental window unit which I have devised for use with a permanent window such as above briefly described, includes a pair of auxil-

2

iary jamb members 17 each consisting of two channel section rails 18 and 19 fashioned from sheet metal and dimensioned so as to fit one over the other in opposing relation as best shown in Fig. 4. The rail 18 has a projecting fin or flange 20 extending longitudinally of its back and constituted by a fold of the metal, said fin or flange being apertured at intervals of its length for passage of the shanks of headed securing devices 21 which take into the shutter stop shoulder 22 on the corresponding jamb 12 of the permanent window frame. The rail 19 on the other hand is formed along its back with an outwardly offset box bead 23 for a purpose later on disclosed. Due to engagement of the rails 18 and 19 in the manner described, the auxiliary jamb members 17 can be adjusted for width, wherefore it is possible to adapt the unit to permanent windows which may vary slightly in their crosswise dimensions, the adjustments being fixable by clamp screws 25 of which the shanks threadedly engage in transverse registering slots 26 and 27 in the outer side faces of said parts.

The supplemental window unit of my invention further includes upper and lower auxiliary sashes 30 and 31, those shown being glazed and having frame bars formed from sheet metal. Except for differing somewhat in height, the sashes 30 and 31 are generally similar in their construction.

The frame bars 32 of the upper sash 30 are all of Z cross section and welded or otherwise permanently secured at corners, with resultant provision of a rectangular perimetric recess for the glass pane 33 whereof the edges are bound with treated tape 35 of felt or the like for weather tightness, retainment being effected by sheathing strips 36 of spring metal which are formed with retroversions to snugly engage over the projecting flanges of the sash frame and which are engaged over and press against the felt strips at the outside of the sash. The sheathing strip 36a for the top bar of the sash 30 provides a retaining channel 37 for packing 38 which seals against an added wooden strip 39 on the lintel 10 of the permanent window frame. The top and side bars 40 of the lower sash are likewise fashioned to Z section from stout sheet metal, but the bottom bar 41 thereof is of channel section and formed with upwardly and downwardly projecting flanges. To the front of the bottom bar 41 of the lower sash is suitably secured a flat spring strip 42 of corresponding width with resultant provision not only of a perimetric recess for the pane 43 but also of a retaining groove for packing 45 along the bottom of said sash to seal against the top of a sill

adapter 46 which is also included in my improved supplemental window and which will presently be again referred to.

Engaging with a clamp fit over the box beads of the auxiliary jamb members 17 are channel section sash guiding strips 50 of which one is separately illustrated in Fig. 8 said strips being of spring metal and jointly providing grooves 51 and 52 for the sashes 30 and 31, the outer walls 53 and 54 of said grooves 51 and 52 respectively extending down and up approximately to a level midway of the height of the window. The projecting side edge flanges of the sashes 30 and 31 are engaged in the grooves of the guide strips 50 in the manner instanced in Figs. 4 and 6. A weathering strip indicated at 55 in Fig. 2 insures against the entry of air or moisture through the interval between the bottom bar of the upper sash 30 and the top bar of the lower sash 31. As shown, the weathering strip 55 is fixedly incorporated with the bottom bar of the upper sash 30 and has a rounded spring tongue 56 which frictionally engages the top bar of the lower sash 31 at the front or outer side. After being engaged within its guide grooves and raised to abut the lintel of the permanent window, the upper sash 30 is locked in position by means of slide bolts 57 confined in housings 58 on the bottom bar of said sash and engaged in suitably located apertures 59 in the inner faces of the box or parting beads of the supplemental jamb members 17, see Fig. 5. The lower sash 31 is similarly provided on its bottom bar with latch bolts 60 which are selectively engageable with apertures 61 at different levels in the box or parting beads of the guide strips 17 to hold said sash variously adjusted when ventilation is desired.

The sill adapter 46 is engaged at its ends in the grooves of the auxiliary jamb members 17 and is formed by two strip parts 62 and 63 of sheet metal which are secured together by screw bolts 64, the strip 62 being initially longer than the strip 63 and having its ends lapped about the ends of the strip 63 as shown at 65 in Fig. 6. From Fig. 3 it will be observed that the strip 62 is plain and flat, while the strip 63 has an inward flange 66 at the top which overreaches the top edge of the strip 62 and affords a surface against which the packing at the bottom edge of the lower auxiliary sash 31 seals. Permanently attached to the outer face of the part 62 adjacent the bottom by welding or otherwise is a Z section strip 67 which in conjunction with said part provides a retaining recess for weathering 68 which seals against the sill surface of the permanent window frame. By reason of being composed of the two separate parts 62 and 63, the height of the adapter 46 can be made to compensate for differences or inaccuracies in the sill slopes of windows of the same nominal dimensions with assurance that the bars 32 and 40 of the auxiliary sashes 30 and 31 meet properly when said sashes are closed. In any case the height of the adapter 46 will be such that its upper edge will be approximately even with the top 16 of the sill 11. Preferably in practice, the part 62 is initially provided with holes for the shanks of the screw bolts 64, and after the proper position has been determined for it during the installation of the supplemental window, registering holes are punched into the part 63 for through-passage of the bolt shanks. Thus after the bolts 64 are once placed and the associated nuts drawn up, the parts 62 and 63 will be rigidly connected against

the possibility of subsequent displacement in the desired permanent relationship.

In order to prevent the accumulation of rain-water behind the adapter 46 when auxiliary screen sashes (not shown) are substituted for the glazed auxiliary sashes 30 and 31, I have provided devices 70, see Figs. 1, 3, 6 and 7, for raising it slightly from contact with the sill 11 of the permanent window. Each device 70 comprises an eccentric lift cam 71 which, upon being turned counter-clockwise from normal position about a screw stud 72 at the inner side of the adapter reacts with the sill 11 after the manner shown in Fig. 7, each such lift cam having a finger projection 73 for convenience of manipulating it. The stops shown at 74 and 75 in Figs. 6 and 7 cooperate with the finger projection 73 of the cam 71 in limiting the extent of rotation of the latter. The cams 71 are in practice so proportioned that the lift imparted to the sill adapter is not in excess of the mesh gage of the screens. Thus insects are prevented from entering through the water-escape clearance beneath the adapter.

Due to the provision of the sill adapter proportioned as just described, I am able to shorten the height of the lower auxiliary sash 31 so that it, as well as the upper auxiliary sash, can be removed from within-doors through the permanent window after the lower sash of the latter is raised. The procedure is as follows: The sash 31 is first elevated to the position shown in dot-and-dash lines in Fig. 9 until it is clear of the top ends of the walls 54 of its guide grooves, then dropped and swung inwardly as shown in full lines in Fig. 9, with its bottom edge amply clearing the top 16 of the sill 11. With the lower auxiliary sash 31 out of the way, the upper auxiliary sash 30 is released and dropped until it clears the bottom ends of the outer walls 53 of its guide grooves 51 whereupon it too can be angularly manoeuvred and finally withdrawn inwardly through the open main window in the same manner as the lower auxiliary sash.

Having thus described my invention, I claim:

1. A supplemental window adapted to be set in a frame of a permanent window, said supplemental window including auxiliary jamb members with means for securing them to the jambs of the permanent window frame, each such auxiliary jamb member comprising two opposingly-arranged interfitting channel strips of sheet material which are relatively adjustable so that compensation can be made for crosswise inaccuracies of the permanent window frame and which have registering transverse slots at intervals of their lengths; screws with their shanks threadedly engaging in the registering slot pairs of the strips to secure said strips against relative displacement; upper and lower auxiliary sashes; and means on the inner strips of the respective auxiliary jamb members for guiding the auxiliary

2. A supplemental window according to claim 1, wherein the outer channel strip of each auxiliary jamb member is formed with a lateral flange which is adapted to bear against a shutter stop on the corresponding permanent jamb; and wherein the securing means comprises headed fastening elements whereof the shanks are passed through the lateral flanges of the auxiliary jamb members and engage into the shutter stops of the permanent window.

3. A supplemental window of the character described including sliding auxiliary sashes; auxil-

lary jamb members with means for securing them to the fixed jambs of a permanent window frame, each such auxiliary jamb member being formed of parts which are relatively adjustable laterally so that compensation can be made for crosswise inaccuracies of the permanent window frame, and each having a longitudinal box bead on its inner face; and a channel section strip of sheet metal engaging over the box bead of each auxiliary jamb member, said strip having lateral retroversions providing guide grooves for the auxiliary sliding sashes.

4. A supplemental window of the character described including sliding auxiliary sashes; auxiliary jamb members with means for securing them to the fixed jambs of a permanent window frame, each such auxiliary jamb member being formed of parts which are relatively adjustable laterally so that compensation can be made for crosswise inaccuracies of the permanent window frame, and each having a longitudinal box bead on its inner face; and a channel section strip of sheet metal engaging over the box bead of each auxiliary jamb member, said strip having lateral retroversions providing guide grooves for the auxiliary sliding sashes, latch bolts on the lower bar of the upper sash engageable with apertures in the box beads of the auxiliary jambs to hold said sash in fixed position; and latch bolts on the bottom bar of the lower sash selectively engageable into apertures at different levels in the box beads of said auxiliary jambs when ventilation is desired.

5. A supplemental window adapted to be set into the frame of a permanent window having side jambs, upper and lower sliding sashes and a sloping water shedding sill, said supplemental window comprising auxiliary jamb strips adapted to be secured to the jambs of the permanent window, said auxiliary strips being provided with parallel inner and outer sash guiding grooves whereof the remote walls respectively extend downward and upward to a level approximately midway of the height of the supplemental window; glazed auxiliary upper and lower sashes slidable in the outer and inner guide grooves of the auxiliary jamb members; and a sill adapter onto which a lower auxiliary sash closes, said adapter being engaged in the side grooves for the latter sash, and being of such height that

50

its upper edge is substantially on a level with the top of the slope of the permanent window sill so that said sash can be angularly manipulated and removed from within doors after being raised to a level above the tops of the retaining walls of its guide grooves and a screen sash substituted in its place.

6. The invention according to claim 5, wherein the adapter consists of two sheet metal parts, one having a lateral flange to overreach the top of the other and provide a contact surface for the bottom edge of the lower auxiliary sash, and said other part having its ends lapped around the ends of the first part.

10 7. The invention according to claim 5, wherein the adapter is provided with means for adjusting it vertically when used with a screen sash, to permit drainage of rain water which would otherwise be trapped behind it on the window sill.

15 8. The invention according to claim 5, wherein the adapter is provided with rotatable cam devices for reacting with the sill and raising it slightly when said adapter is used with a screen sash, to permit drainage of rain water which would otherwise be trapped behind it on the window sill.

20 9. The invention according to claim 5, wherein the adapter is composed of components capable of being shifted vertically relative to each other to compensate for inaccuracies or variations in the sill slope of a permanent window of the same nominal dimensions, and including means for securing the adapter components in fixed relation after the proper setting has been determined.

30 HENRY N. RENTON.
